UNITED STATES PATENT OFFICE.

GEORGE W. MUDD, OF COLUMBUS, OHIO.

STOVE-PIPE DAMPER.

SPECIFICATION forming part of Letters Patent No. 334,715, dated January 19, 1886.

Application filed December 19, 1884. Serial No. 150,886. (No model.)

To all whom it may concern:

Be it known that I, GEORGE W. MUDD, a citizen of the United States of America, residing at the city of Columbus, in the county 5 of Franklin and State of Ohio, have invented certain new and useful Improvements in Stove-Pipe Dampers; and I do hereby declare the following to be a full, clear, and exact description of the invention, such as will enable others skilled in the art to which it appertains to make and use the same.

My invention relates to an improvement in single-bearing stove-pipe dampers; and it consists, first, of a handle which forms the spindle 15 and guide, and, second, of a damper-plate provided with a slotted head to receive the spindle, and these in combination with other features, all as more fully hereinafter described.

My invention is illustrated in the accompanying drawings, in which Figure 1 is a longitudinal section; Fig. 2, a separate view of the handle, and Fig. 3 a detached view of the damper-plate and slotted head.

In the drawings, A represents a section of 25 pipe and B the damper, which may be formed of any circular piece of metal.

C is the handle and spindle, consisting of a wooden cross-piece, d, and the spindle part E, provided with round portion f, the collar g, and at its lower end with the shank portion H, terminating in the lugs i i. The plate B has cast or otherwise made integral therewith a boss, L, provided with a slot, M, and open notches n n, forming channels at right 35 angles to the slot M. The slot M is adapted to receive the end of the spindle-shank, and when passed through the same and the handle is turned, the lugs i i rest and are secured in the channels n. To provide room in which to

thus turn the shank, the plate is provided 4 with the recess o. The boss L is also provided with a collar or rim, p, on which to place a washer, R, fitting snugly against the inner wall of the pipe.

S is a cup or sleeve placed over the spindle, 4 bearing against the collar g, and constituting a chamber for a spiral spring, t, which surrounds the round portion f of the spindle and bears directly against the pipe.

To adapt the invention to use, the cup S is 5 put on the spindle, the spiral spring inserted in the cup around the spindle, the shank of the handle then inserted through a hole in the pipe, the washer and plate put in place, and the shank inserted through the boss L and 5 turned until the lugs i rest in the notches n. It will be seen that there are but five separate parts in this damper, consisting of the plate, washer, handle, sleeve, and spring, thus giving simplicity to the structure, removing 6 friction, &c.

What I claim is—

A stove-pipe damper comprising the handle provided with the collar g, the spindle part E, shank H, and lugs i i, in combination with the 6 separate cup, spiral spring, the washer, and the damper-plate, the latter having formed on one edge and integral therewith the double slotted boss L, adapted to receive the washer, and having the recess o in the plate beyond 7 said boss, to aid in the operation of the handle, substantially as described.

In testimony whereof I affix my signature in presence of two witnesses.

GEORGE W. MUDD.
